MULTIPLE CUTTER SHAVER HAVING CONTINUOUS SHAVING SURFACE

Ivo H. Brewer, 509 Maple Ridge Ave., Ann Arbor, Mich.
Filed Aug. 1, 1962, Ser. No. 214,009

2 Claims. (Cl. 30—43.6)

The present invention relates to improvements in electric shavers and more particularly to improvements in the cutting head and the arrangement for driving the cutting elements thereof.

It is conventional practice in the electric shaver art to provide shavers with either reciprocating cutting blades or continuously rotating cutting blades. Each type of shaver has advantages and disadvantages when considered with the other. One of the problems that exists in connection with the rotary type shaver is the limited effective cutting area that is available on the shaver head. This occurs because shavers of this type have heretofore had the cutter blades revolving about a single axis. To overcome this difficulty, efforts have been made to provide multiple rotary cutters, but such arrangements do not provide a uniform uninterrupted shaving surface across the width of the electric shaver.

It is an object of the present invention to provide an improved electric shaver of the rotary type which is constructed and arranged to provide a uniform, uninterrupted shaving surface extending across the width of the shaver head.

It is still another object of the present invention to provide an improved electric shaver of the rotary type which has a non-circular shaving surface and an associated cutter assembly adapted to travel in a rotary, but non-circular path, so that a shaving surface of desired configuration is realized.

It is still another object of the present invention to provide an improved electric shaver of the foregoing character which is constructed and arranged so that the cutting elements are constantly urged against the comb of the shaver thereby assuring that uniform cutting characteristics are provided and that constant compensation for wear between the comb and the cutting blades is assured.

It is still another object of the present invention to provide an improved shaver of the foregoing character which has a maximum number of cutting blades adapted to travel continuously at substantially a uniform speed across apertures in the comb thereby assuring uniform cutting characteristics across the shaving surface of the shaver head.

It is still another object of the present invention to provide an electric shaver of the foregoing character which has a unique drive mechanism for moving the cutting blades continuously in an endless path across the inner surface of the comb of the shaver head.

Other objects of this invention will appear in the following description and appended claims, reference being had to the accompanying drawings forming a part of this specification wherein like reference characters designate corresponding parts in the several views.

In the drawing:

FIGURE 1 is a top plan view of the head of an electric shaver embodying the present invention, with portions of the head removed to illustrate internal parts of the shaver and with other parts shown in section;

FIGURE 2 is a fragmentary sectional view taken on the line 2—2 of FIGURE 1; and

FIGURE 3 is a fragmentary sectional view taken on the lines 3—3 of FIGURE 1.

Before explaining the present invention in detail, it is to be understood that the invention is not limited in its application to the details of construction and arrange-

2

ment of parts illustrated in the accompanying drawing, since the invention is capable of other embodiments and of being practiced or carried out in various ways. Also it is to be understood that the phraseology or terminology employed herein is for the purpose of description and not of limitation.

Referring now to the drawings, the invention will be described in greater detail. The electric shaver 10 has a housing 12 in the lower portion of which is enclosed an electric motor (not shown) which is adapted to turn the shaft 14. The upper end of the housing 12 is closed by the head member 16 which is hingedly connected to the housing 12 by suitable hinge means, shown at 18, and a spring clip (not shown).

The shaft 14 has a drive gear 20 on its upper end and which is in mesh with the gears 22 and 24, and all three of such gears are enclosed in the gear housing 26 supported by screws 28 from the inner wall 30 of the housing 12. Bearing means 32 are positioned in the walls of the gear housing 26 in which the shaft 14 and the shafts 34 and 36 are journaled. The shafts 34 and 36 are similarly arranged, and therefore, only the internal construction and arrangement of the shaft 34 will be described.

As seen in FIGURE 2, the shaft 34 extends upwardly from the gear housing 26 and slidably fits into the sleeve 38. A second shaft 40 is fitted into the sleeve 38 and is held therein against turning. Preferably the shaft 40 is press-fitted into the sleeve 38. The axially aligned shafts 34 and 40 have axially aligned holes 42 and 44 therein in which is retained in compression a coil spring 45 so as to urge the shaft 40 in an upward direction. The shafts 34 and 40 are held against relative rotation by means of a tongue 46 on the end of the shaft 40 which fits into a transverse groove 48 in the shaft 34. Thus, it can be seen that when the shaft 14 is turned by the electric motor (not shown), the gear 20 will be turned which will result in gear 22, shaft 34, and shaft 40 turning therewith. Similarly, when shaft 14 is turned, gear 24, shaft 36, and shaft 50 will be turned. Thus, shafts 40 and 50 will turn at the same speed and in the same direction by virtue of the drive arrangement described.

The arrangement for driving the cutting elements of the electric shaver 10 by means of the two shafts 40 and 50 will be next described. Referring again to FIGURE 2, a tongue 52 can be seen on the end of the shaft 40, which tongue extends into a transverse groove 54 in the drive member 56. The latter is press-fitted into the bearing member 58 which in turn is press-fitted into the hexagonal drive member 60. Thus, when the shaft 40 is rotated, the drive member 56, the bearing member 58 and the hexagonal drive member 60 are rotated therewith. The fit between the tongue 52 and the groove 54 in the drive member 56 is a loose fit so that when the head member 16 is opened by pivoting about the hinge structure 18, the drive member 56 will readily slide away from the tongue 52. The bearing member 58 can be any suitable type of bearing which will provide a proper bearing surface against the wall of the opening 62 at 64 in the stationary plate 64.

The shaft 50 is similarly operatively connected to the hexagonal drive member 66 by means of the tongue 68, groove 70, drive member 72 and bearing 74. From the foregoing description, it can be readily understood that the hexagonal drive members 60 and 66 are adapted to be turned together at synchronized speeds.

The plate 64 forms the bottom wall of the head member 16 and connected thereto by a plurality of screws 76 is the comb or comb member 78. The upper surface 70 of the comb member 78 has a plurality of thin slits 79 formed therein which are adapted to receive the hair that is to be cut when using the electric shaver. These slits

79 are arranged generally in an oval path and are arranged in perpendicular relationship to the path. Only a portion of this path is shown in FIGURE 1, but it can be readily understood that this oval path is endless in character and covers the entire shaving portion of the electric shaver. Press-fitted or suitably secured against turning with respect to the comb member 78 are bearing members 81 which slidably fit into the upper ends of the hexagonal drive members 60 and 66 and aid in maintaining the members 60 and 66 in proper alignment.

Positioned between the plate 64 and the comb member 78 is a chain-like endless cutter assembly 80 which is adapted to be driven by the hexagonal drive members 60 and 66. The endless cutter assembly is made up of a plurality of cutter elements 82 which are joined by links 84. Each of the cutter elements 82 is a block-like member having a slot 86 extending longitudinally through the inner side thereof and having a plurality of cutting blades 88 projecting upwardly from its upper surface. Fitting into the slots 86 are links 90 which are pivotally connected at their opposite ends to one another and to the cutter elements 82 by a plurality of pins 92. The links 90 each have a single tongue 94 on one end and a pair of spaced tongues 96 on the other end adapted for making this chain-like connection between the adjacent cutter elements 82. From the foregoing description, it is believed clear that the cutter elements 82 are joined together to form a chain-like endless cutter assembly which is adapted to travel in the same endless oval path as defined by the slits 79 and with the cutting blades 88 traveling against the inner surface of the comb member 78 in the region of the slits 79.

As can be seen in FIGURE 1, the cutter elements 82 are approximately of the same width as each of the circumferential faces of the hexagonal drive members 60 and 66 so that the cutter elements 82 will, in effect, be held in mesh with the hexagonal drive members 60 and 66 when the latter are rotated about their axes. Each of the cutter elements 82 fits against one of the surfaces of the hexagonal drive members 60 and 66 and travels around the axes of the drive members 60 and 66 for one half revolution, after which the cutter elements 82 depart tangentially from the axes of rotation of the drive elements 60 and 66 and travel in a straight line toward the other of the drive elements 60 and 66. For the purpose of guiding and maintaining the chain assembly in proper alignment between the drive elements 60 and 66, a block 98 is provided which is suitably secured in a stationary position to a plate 64 by any suitable means such as the screw 100 and the pins 102. Also, in order to maintain the cutting blades 88 in constant sliding engagement with the inner surface of the comb member 78, a track or bearing plate 104 is provided which has essentially the same configuration as the path of travel of the cutter assembly 80, and a spring element 106 is provided for constantly urging the bearing plate 104 upwardly against the cutter assembly 80, and thereby urging the cutting blades 88 against the underside of the comb member 78.

In operation, it can be understood from the foregoing description that the electric motor (not shown) that is connected to the shaft 14 serves to drive the chain-like endless cutter assembly 80 continuously in one direction and the cutting blades 88 are constantly urged against the underside of the comb member 78. It is believed readily apparent that the cutting blades 88 will travel past the slits 79 at substantially the same velocity throughout their entire path of travel. The thin slits 79 are perpendicular to the path of travel of the cutter elements 82, and from an observation of FIGURE 1, it can be seen that the cutting blades 88 are uniformly inclined

at an angle to the alignment of the thin slits 79 so as to provide a most effective cutting action. It can also be seen that shaving surfaces of other desired configurations can be obtained by varying the dimensions and locations of the hexagonal drive members 60 and 66. Preferably, the arrangement shown in the drawings will be employed so that a relatively wide shaving surface in which uniform cutting action is obtained will be realized.

When it is desired to raise the head member 16 for cleaning or repair purposes, this is accomplished merely by pivoting the head member 16 about the hinge means 18 after release of the detent spring clip (not shown). If it becomes necessary to remove the comb member 78, this can be accomplished by unscrewing the screws 76.

Having thus described my invention, I claim:

1. In an electric shaver, a comb having outer and inner surfaces and a plurality of apertures arranged in a generally oval path for receiving through the outer surface of the comb the hair to be cut, a plurality of cutter elements operatively linked together to provide a chain-like endless cutter element assembly for continuous travel in said oval path with said cutter elements in engagement with the lower surface of the comb, a bearing surface in engagement with said cutter element assembly on the opposite surface from that which is in engagement with said comb, spring means mounted to urge said bearing surface against said cutter element assembly and said cutter element assembly against said comb, and drive means including rotary elements centered within opposite ends of said oval path and operatively connected to said cutter element assembly for driving the same continuously in one direction in said oval path.

2. In an electric shaver, a comb having outer and inner surfaces and a plurality of apertures arranged in a generally oval path for receiving through the outer surface of the comb the hair to be cut, a plurality of cutter elements operatively linked together to provide a generally oval-shaped chain-like endless cutter element assembly for continuous travel in one direction in said oval path with said cutter elements in engagement with the lower surface of said comb, said cutter elements each having a side surface facing inwardly with respect to the oval-shaped assembly, and drive means including rotary elements centered within opposite ends of the oval-shaped assembly and having a plurality of surfaces circumferentially arranged for engagement with corresponding inwardly facing ones of said cutter elements for driving said oval-shaped assembly continuously in one direction in the oval path.
